US0D1020740S

(12) **United States Design Patent** (10) Patent No.: **US D1,020,740 S**
(45) Date of Patent: ** Apr. 2, 2024

(54) **SMART WATCH**

(71) Applicant: **Samsung Electronics Co., Ltd.**, Suwon-si (KR)

(72) Inventors: **Jinwook Kim**, Suwon-si (KR); **Yunjin Kim**, Suwon-si (KR)

(73) Assignee: **SAMSUNG ELECTRONICS CO., LTD.**, Suwon-si (KR)

(**) Term: **15 Years**

(21) Appl. No.: **29/855,806**

(22) Filed: **Oct. 7, 2022**

(30) **Foreign Application Priority Data**

Jul. 7, 2022 (KR) 30-2022-0027367

(57) **CLAIM**

The ornamental design for a smart watch, as shown and described.

DESCRIPTION

FIG. 1 is a front perspective view of a smart watch showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dashed broken lines in the figures depict portions of the smart watch that form no part of the claimed design.

1 Claim, 7 Drawing Sheets
